US00D843015S

(12) **United States Design Patent** (10) **Patent No.:** **US D843,015 S**
(45) **Date of Patent:** **** Mar. 12, 2019**

(54) **FRAMING ACCESSORY WITH A RIBBED
AND PERFORATED FLANGE**

(71) Applicant: **CLARKWESTERN DIETRICH
BUILDING SYSTEMS LLC**, West
Chester, OH (US)

(72) Inventors: **Nick Joseph Apanovich**, Tampa, FL
(US); **Erenio Reyes**, Miami, FL (US);
Hernando Garcia, Doral, FL (US);
James Michael Wielinga, Parkland, FL
(US)

(73) Assignee: **Clarkwestern Dietrich Building
Systems LLC**, West Chester, OH (US)

(**) Term: **15 Years**

(21) Appl. No.: **29/590,216**

(22) Filed: **Jan. 9, 2017**

(51) **LOC (11) Cl. 25-01**

CLAIM

The ornamental design for a framing accessory with a ribbed and perforated flange, as shown and described.

DESCRIPTION

FIG. 1 is a top perspective view of a framing accessory with a ribbed and perforated flange showing our new design; FIG. 2 is a bottom perspective view of the framing accessory with a ribbed and perforated flange of FIG. 1; FIG. 3 is a front elevational view of the framing accessory with a ribbed and perforated flange of FIG. 1; FIG. 4 is a rear elevational view of the framing accessory with a ribbed and perforated flange of FIG. 1; FIG. 5 is a right elevational view of the framing accessory with a ribbed and perforated flange of FIG. 1; FIG. 6 is a left elevational view of the framing accessory with a ribbed and perforated flange of FIG. 1; FIG. 7 is a top plan view of the framing accessory with a ribbed and perforated flange of FIG. 1; FIG. 8 is a bottom plan view of the framing accessory with a ribbed and perforated flange of FIG. 1; FIG. 9 is another top perspective view of the framing accessory with a ribbed and perforated flange, showing our new design in an alternate environment of use; FIG. 10 is a bottom perspective view of the framing accessory with a ribbed and perforated flange of FIG. 9; FIG. 11 is a rear elevational view of the framing accessory with a ribbed and perforated flange of FIG. 9; FIG. 12 is a front elevational view of the framing accessory with a ribbed and perforated flange of FIG. 9; FIG. 13 is a right elevational view of the framing accessory with a ribbed and perforated flange of FIG. 9;

FIG. 14 is a left elevational view of the framing accessory with a ribbed and perforated flange of FIG. 9; FIG. 15 is a top plan view of the framing accessory with a ribbed and perforated flange of FIG. 9; FIG. 16 is a bottom plan view of the framing accessory with a ribbed and perforated flange of FIG. 9; FIG. 17 is another top perspective view of the framing accessory with a ribbed and perforated flange, showing our new design in an alternate environment of use; FIG. 18 is a bottom perspective view of the framing accessory with a ribbed and perforated flange of FIG. 17; FIG. 19 is a front elevational view of the framing accessory with a ribbed and perforated flange of FIG. 17; FIG. 20 is a rear elevational view of the framing accessory with a ribbed and perforated flange of FIG. 17; FIG. 21 is a right elevational view of the framing accessory with a ribbed and perforated flange of FIG. 17; FIG. 22 is a left elevational view of the framing accessory with a ribbed and perforated flange of FIG. 17; FIG. 23 is a top plan view of the framing accessory with a ribbed and perforated flange of FIG. 17; and, FIG. 24 is a bottom plan view of the framing accessory with a ribbed and perforated flange of FIG. 17.

The broken lines in FIGS. 1-24 are included for purposes of illustrating portions of the framing accessory with a ribbed and perforated flange that form no part of the claimed design. The framing accessory with a ribbed and perforated flange is shown with a symbolic break in its length. The symbolic break is depicted using dash-dot lines and brackets. The appearance of any portion of the framing accessory with a ribbed and perforated flange between and including the break lines forms no part of the claimed design.
